STAPLING MACHINE

Stephen A. Crosby, Jackson Heights, N. Y., assignor to Speed Products Company, New York, N. Y.

Application July 10, 1939, Serial No. 283,692

11 Claims. (Cl. 1—3)

The present invention has to do with stapling machines and particularly is concerned with a long reach stapling machine. The object of the invention is realized in providing an effective long reach stapling machine having spaced and reinforced longitudinally arranged and transversely spaced vertical guide wings comprising stop means cooperating with a resilient cantilever beam to limit upward displacement of the staple and staple ejector plunger carrying arm vertically guided by the spaced wings and fixedly retained by and overhanging the free end of the beam. Further objects, advantages, and functional and structural aspects of the invention will be apparent from the following detailed description viewed in the light of the accompanying drawings wherein:

Fig. 1 is a perspective view of the long reach stapling machine according to my invention illustrating the staple carrying arm in a partially opened relation and the supporting cantilever beam in its normally raised position.

Fig. 2 is a side elevational view of Fig. 1 illustrating the staple carrying arm partly broken and partly in section.

Fig. 3 is a plan view of Fig. 2.

Fig. 4 is a side elevational view of the long reach stapling machine showing the arm thereof depressed against the anvil of the base and its staple ejecting plunger raised.

Fig. 5 is a view similar to Fig. 4 showing the staple carrying arm and the staple ejecting plunger thereof depressed.

Fig. 6 illustrates an exploded view of the base, the cantilever spring, and the braces or wings for guiding the staple carrying arm.

Fig. 7 is a sectional view on the line 7—7 of Fig. 3.

Fig. 8 is a plan view of the long reach stapling machine with the cover for the staple magazine of the staple carrying arm swung to a fully opened position.

Fig. 9 is a side view of Fig. 8 partly broken away to illustrate the manner in which the rear part of the beam serves to limit rearward displacement of the pivoted closure.

Figs. 10 to 12 are perspective views of the plunger, intervenor, and mount, and

Figs. 13 to 16 inclusive are side views showing the progressive action of the stroke control mechanism during a complete down stroke of the plunger and during the beginning of the return stroke thereof.

Illustrative of the embodiment disclosed, the long reach stapling machine is generally denoted

L and comprises a channeled sheet metal base B, spaced sheet metal wings W, a staple carrying metal arm or casing A and a sheet metal support or cantilever beam C to which the arm A is fixedly secured.

The wings W are relatively elongated members and are appreciably longer than the length of the staple carrying arm A. These wings each include a longitudinally disposed reinforcing bead 10. The rear portion of these wings include an inwardly turned perforated flange 11 mounted on the perforated offset tail portion 12 of the beam C which in turn is located on the rear perforated part 13 of base B and suitable fastening means 14 in the form of rivets as shown are utilized to secure tail 12 fixedly between inwardly extending flanges 11 and the rear portion 13 of the base.

With the rear ends 11 of the wings W firmly secured to the base, the lower edges 15 thereof are appreciably spaced from the upper surface of the base. As shown the wings are tapered and each includes at its free ends a depending curved stop lip 16 cooperating with the marginal portions of the front end 17 of the cantilever beam C to limit upward displacement thereof.

The magazine M of arm or casing A is fixedly anchored to the forward end 17 of beam C which has its body 18 offset in respect to the rear portion 12, the arrangement being such that the inherent resiliency of the sheet metal body 18 automatically retracts the latter to position the front end 17 of the beam against the stop lips 16. Thus the forward end of the beam is normally elevated and in such relation the front part of the staple carrying arm A in part projects forwardly of the front end of the resilient cantilever beam C since the bottom wall 19 of magazine M is fixedly secured to the front end 17 of the beam by suitable hollow rivets 20 struck out of end 17 and riveted to the bottom wall of the magazine as shown.

According to the invention the well known "Swingline" type of arm A is shown mounted at the front end of the beam although other types of staple and staple ejecting plunger carrying arms or casings may be employed. However for purposes of disclosure arm A may be said to comprise (Fig. 2) the magazine M containing the fixed rail R on which staples 21 are slidably guided and urged forwardly by a suitable follower F slidably interlocked with the rail and having a hook H (Fig. 8) to which the lower end 22 of a spring 23 is connected.

The intermediate portion 24 of this spring 23 is trained over a roller 25 rotatably carried by a

slidably retained pin 28' carried by the swingable cover 26 of arm A for the magazine M. The cover and magazine have complementary locating means in the form of a lug 28 and recess 29 for properly locating the cover relative to the magazine upon closing of the cover which has ears 30 rotatably mounted on the rear fulcrum pin 31 carried by the magazine. It should be observed however that the end 34' of the upper reach 32 of the normally compressed spring 23 is retained by a lug 33 struck out of the cover 26.

The roller 25 cooperates to urge latch 34 slidably guided in slots 35 in the spaced sides of the cover 26 and in the spaced sides of the fixed front sheath 27 which constitutes the fore part of cover 26 to disengageably interlock with notches 36 (Fig. 1) in the extensions 37 of the magazine when the cover is closed, that is, swung towards and against the magazine. Thus with the cover closed the follower R is urged forwardly by the looped spring 23 to present the foremost staple in the magazine in the vertical raceway 40 and underneath the rectilinearly movable blade 41 of a staple ejecting plunger P vertically and slidably guided at the front end of the cover and normally held in a raised relation by the leaf spring 42. The staple carrying arm A has been just briefly described since it may be substituted by other functionally equivalent means for containing staples and for ejecting one of the latter therefrom at a time when the cap 45 carried by the plunger is depressed.

If the arm is closed the plunger P is in a normally raised position and the beam C is against the stop lips 16 of wings W. The relatively long gap G is defined by magazine M and the beam C with the upper surface of the base to permit the insertion of paper or any other material to be stapled an appreciable distance into this gap and such entry thereof can be made at least to the extent of the length of this gap which is immeasurably greater than the length of the staple carrying arm.

With several sheets of paper or the like to be fastened, inserted into the gap G and positioned on the base, the reciprocably guided plunger in the cover 26 may be actuated by applying a downwardly directed pressure to cap 45. This action at first merely flexes the beam, that is, the forward end 17 thereof moves downwardly away from lips 16 (Fig. 4) until the magazine M strikes the sheets (not shown) to be stapled above the fixed anvil 46 carried by the base. Upon continued application of the downwardly directed pressure on cap 45, the plunger P slides downwardly relative to the arm A (Fig. 5) and the blade 41 thereof drives the foremost staple out of raceway 40 in the magazine through the sheets of paper or the like to be clinched thereagainst by the anvil and of course at this time the forward end of the beam remains curved and flexed as shown.

Where the stapling operation is completed, the operator removes the downwardly directed pressure on the cap, and the free end of the beam 65 retracts or recoils carrying with it arm A. Thereafter stops 16 limit such retraction of the beam and during the retraction of the beam the plunger is restored to its normally raised position by spring 42.

Since the cover may be swung rearwardly of the magazine in the manner indicated in Fig. 9, of course after the slidable latch 34 has disengaged from the magazine, the magazine is fully 75 opened and can be conveniently supplied with

staples. In such position of the cover however the rear end of the cap 45 which may be of rubber is seated on the intermediate part of the beam which constitutes stop means to limit rearward swingable movement of the cover.

A staple control mechanism of the type disclosed in my copending application, S. N. 146,708, filed June 7, 1937, may be employed to allow the ejection of the staple in the raceway 40 on each complete downward stroke of the plunger and in this connection the slidable and tilttable intervenor 50 normally urged forwardly by spring 51 is against abutment 52 of the plunger P when the latter is in its normally raised position (Fig. 2) and when the plunger is moved downwardly the intervenor 50 automatically is shifted forwardly between the abutment 52 and the fixed mount 53 which constitutes stop means for abutment 52 of the plunger in its normally raised position. Thus after a slight downward displacement of the plunger a complete return stroke cannot be made. But such complete return stroke can be made if the plunger is fully depressed since on the down stroke inclined cam faces 54 of the spaced sides of the plunger shift lugs 55 of the intervenor onto the lower stepped portions 56 of the fixed mount 53. Hence the intervenor 50 is held fully out of the way until the complete down stroke of the plunger has been completed. However on the retraction of the plunger, horizontal walls or abutments 58 in the sides of the plunger raise lugs 55 out of the lower stopped portions 56 and onto the upper steps 57 of the mount at which time abutment 52 is stopped against the fixed mount 53, and spring 51 retracts the intervenor to contact the rear face of this abutment 52. Where an incomplete down stroke is made, blade 41 closes the raceway 41. Thus a complete down stroke is first necessary before a complete return stroke can be made at which time a staple can be urged into raceway 40 by the follower R since on a partial downward stroke of the plunger the driving blade of the latter 45 serves to close raceway 40.

As many changes could be made in the above described construction and many widely different species or structural embodiments could be devised without departing from the scope thereof, it is intended that all matter hereinbefore described in the specification and illustrated in the accompanying drawings shall be interpreted as illustrative and not in a limiting sense.

I claim:

55 1. In a long reach stapling machine, a base, wing means carried by said base, a sensibly resilient cantilever beam secured to said base and substantially coextensive with the length of said wing means and having a front movable end limited in one direction of movement by said wing means, and staple carrying and ejecting means mounted exclusively on said beam.

2. In a stapling machine, a base, an anvil sustained by said base, spaced wings carried by said base and defining a gap, stop means extending from said wings, a relatively thin cantilever leaf spring substantially coextensive with the length of said wings and bridging said gap transversely thereof and having a forward end normally yieldingly abutting said stop means and a rearwardly disposed fixed end, and staple carrying and ejecting means fixedly carried by said front end and adapted upon downward application of pressure thereon to shift said forward end downwardly and away from said stop

means to arrange said staple carrying and ejecting means and anvil in operative alignment, said front end automatically retracting pursuant to removal of said pressure to abut said stop means for limiting bodily retraction of said staple carrying and ejecting means.

3. In combination, an elongated base having an anvil at the forward end thereof, wings disposed vertically relative to said base and transversely spaced thereof to define a gap, a cantilever leaf spring support horizontally bridging said gap and substantially coextensive with the length of said wings and having a rear fixed end and embodying an intermediate portion and a front end spaced from said base, stop means above said base, said front end normally abutting said stop means and characterizing a seat, and staple ejecting means mounted on said seat and in part overhanging the latter and said wings and vertically and movably guided in said gap by and between said wings for cooperating with said anvil upon application of downward pressure thereon whereby said front end is flexed downwardly and away from said stop means.

4. In a long reach stapling machine, a base, 25 spaced wings disposed longitudinally of and carried by said base, a cantilever beam having a rear end fixedly interposed between said wings and base and including a free end abutting said wings, and staple carrying and ejecting means secured to said free end.

5. In a stapling machine, an elongated base, wing means superimposed in respect to and in part secured to said base and including stop means, a resilient beam having a rear end fixedly interposed between said wings and base and including a free end abutting said stop means, and staple carrying and ejecting means secured to said free end and movably guided by said wings.

6. In combination, a base, guide means carried by said base, a leaf spring substantially coextensive with the length of said guide means and having one end secured to said base and having a free end normally yieldingly abutting said guide means, and staple ejecting means mounted on said free end.

7. In combination, an elongated base having an anvil, wings disposed vertically relative to said base and transversely spaced thereof and having rear portions secured thereto and remaining portions spaced therefrom, a cantilever spring having a rear portion fixedly secured relative to said base and including a front portion spaced from and normally removably abutting at least one of said wings, and staple ejecting means mounted in part on and overhanging said front portion for cooperating with said anvil.

8. In combination, an elongated base having an anvil, wings disposed vertically relative to said base and transversely spaced thereof and

5 having rear portions secured thereto and remaining portions spaced therefrom, a cantilever spring substantially coextensive with the length of said wings and having a rear portion fixedly secured relative to said base and including a front portion appreciably spaced from and normally yieldingly abutting at least one of said wings, and staple ejecting means interposed between said wings and mounted in part on and overhanging said front portion for cooperating with said anvil.

9. In combination, an elongated base having an anvil, wings disposed vertically relative to said base and transversely spaced thereof and having rear portions secured thereto and intermediate and front portions spaced therefrom, lips depending from said front portions, a cantilever spring having a rear portion fixedly secured relative to said base and including a depressible front portion normally and yieldingly abutting said lips and staple ejecting means mounted in part on and overhanging said front portion and movably guided by and between said wings for cooperating with said anvil.

10. In combination, an elongated base having an anvil, wings disposed vertically relative to said base and transversely spaced thereof to define a gap and having inwardly turned flanges, lips depending from said wings at the forward ends thereof, a cantilever offset sensibly resilient support horizontally bridging said gap and having a rear portion interposed between said base and flanges and secured thereto and embodying an intermediate and front portion spaced from said base, said front portion normally removably abutting said lips and characterizing a seat, and staple ejecting means mounted on said seat and vertically and movably guided in said gap by and between said wings for cooperating with said anvil.

11. In combination, an elongated base having an anvil, wings disposed vertically relative to said base and transversely spaced thereof to define a gap and having inwardly turned flanges, 45 lips depending from said wings at the forward ends thereof, a cantilever offset sensible resilient support disposed along the length of said wings and horizontally bridging said gap and having a rear portion interposed between said base and flanges and secured thereto and embodying an intermediate and front portion spaced from said base, said front portion normally removably abutting said lips and characterizing a seat, ribs extending longitudinally 55 along said wings to reinforce the latter, and staple ejecting means mounted in part on and overhanging said seat and vertically and movably guided in said gap by and between said wings for cooperating with said anvil.

STEPHEN A. CROSBY.
